Primary Examiner — T Chase Nelson*Assistant Examiner* — Amanda J Berlinski(74) *Attorney, Agent, or Firm* — Prakash Nama; Global IP Services, PLLC(57) **CLAIM**

The ornamental design for a snorkel mask, as shown.

DESCRIPTION

FIG. 1 is a front elevational view of a snorkel mask showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof;

FIG. 10 is a fourth perspective view thereof;

FIG. 11 is a fifth perspective view thereof;

FIG. 12 is a sixth perspective view thereof;

FIG. 13 is a seventh perspective view thereof; and,

FIG. 14 is an eighth perspective view thereof.
